UNITED STATES PATENT OFFICE.

LE ROY W. FAIRCHILD, OF NEW YORK, N. Y.

DESIGN FOR A PENCIL-CASE.

SPECIFICATION forming part of Design No. 14,965, dated April 22, 1884.

Application filed February 25, 1884. Term of patent 3½ years.

To all whom it may concern:

Be it known that I, LE ROY W. FAIRCHILD, of New York, in the county of New York and State of New York, have invented a certain 5 Design for Cases for Pencils and other Implements, of which the following is a specification.

This invention consists of a new and ornamental design for cases for pencils and similar 10 implements.

The drawing is a front elevation of a case embodying my design.

The design, as shown by the drawing, consists of a series of annular rings or corrugations arranged side by side the entire length of the case, the case having the appearance of being composed of a series of rings placed one upon another, and all secured together at their adjoining edges. The rings or corrugations, 15 as shown, are semicircular or oval in cross-section on their exterior, and when a series of

them are thus united to form a case of the proper length, it presents an appearance that is both pleasing and unique.

To render the design more ornamental, the 25 rings *a* and *b* may be composed of gold or silver, or any suitable contrasting materials and colors, as indicated in the drawing, the different corrugations or rings being arranged in such order as taste or fancy may dictate. 30

What I claim is—

The design for a case for pencils or similar implements, which consists of a tubular body having its exterior surface composed of a series of annular corrugations, rings, or protuberances, semicircular or oval in cross-section, substantially as shown and described. 35

LE ROY W. FAIRCHILD.
